TOY ROCKET

Stefan Apostolescu, New York, N.Y.

Application January 28, 1958, Serial No. 49,428

Term of patent 7 years

(Cl. D34—15)

Fig. 1.

Fig. 2.

Fig. 3.

Fig. 1 is a bottom plan view of a toy rocket showing my new design.

Fig. 2 is a top plan view thereof.

Fig. 3 is a side elevational view thereof.

The dominant feature of my design resides in the portion shown in full line.

I claim:

The ornamental design for a toy rocket, as shown and described.
